UNITED STATES PATENT OFFICE.

JAMES LYONS, OF OGDEN, UTAH.

FREIGHT-CAR DOOR.

1,404,622.

Specification of Letters Patent. Patented Jan. 24, 1922.

Application filed November 5, 1920. Serial No. 421,963.

To all whom it may concern:

Be it known that I, JAMES LYONS, a citizen of the United States, and a resident of Ogden, in the county of Weber and State 5 of Utah, have invented a new and Improved Freight-Car Door, of which the following is a full, clear and exact description.

This invention relates to improvements in freight car doors, an object of the invention being to provide an improved flexible door for box cars.

It is a recognized fact that all box cars after a certain amount of use will sag or bulge out of shape. This causes the ordinary sliding door to jam and results in a great deal of unnecessary trouble and delay when it is desired to load or unload the car.

An object of this invention, therefore, is to provide a door which will buckle when 20 the car bulges and at all times conform to the shape of the side wall of the car so that it will not jam when the box car becomes old and gets out of shape.

A further object is to provide an improved track upon which the door slides and to provide a housing for the track which will effectively protect the same from dampness in inclement weather.

A still further object is to construct the 30 door in a simple and practical manner so that it will be strong and durable and efficient in the uses for which it is intended, and yet will be comparatively inexpensive to manufacture.

With these and other objects in view the invention consists in certain novel features of construction, and combinations and arrangements of parts as will be more fully hereinafter described and pointed out in the 40 claims.

In the accompanying drawings—

Figure 1 is a fragmentary view in side elevation of a freight car body with my improved door attached thereto.

45 Figure 2 is a broken view in transverse section on the staggered line 2—2 of Figure 1.

Figure 3 is a fragmentary view in transverse section through the door illustrating the position of the door when the wall of a 50 car has sagged out of shape.

Referring in detail to the drawings, A represents the side wall of a box car which is provided with the usual door opening and to which my improved door is attached.

55 The door comprises an upper and a lower section 1 and 2 respectively. The upper sec-

tion 1 is provided at its lower edge with a hook-shaped hanger 3 in the form of a metal strip bent along longitudinal lines to give the desired formation. The hanger 60 3 engages a similar strip 4 on the upper edge of the lower door section 2. These two strips serve to hingedly suspend the lower door section from the upper one.

A horizontal track 6 is secured to the side 65 of the car. If desired, this track may be integral with its housing which is in the form of a shelf 7 projecting at right angles from the side of the car above the track 6 and an apron 8 depending from the outer edge of the 70 shelf.

A flange 9 depends from the track 6 within the housing and is accommodated by a groove 10 formed in the upper outer edge of the door section 1, as shown clearly in 75 Figure 2.

U-shaped hangers 11 located in and transversely of the housing are made integral with depending straps 12 located between the flange 9 on the track and the apron 8 80 of the housing and are bolted or otherwise secured to the upper door sections. Pins 13 are supported between the arms of the U and provide mounting for steel balls 14 which roll on the track 6. This construction permits the door to slide with a minimum of friction.

A strip of angle iron 15, forming a flange, is secured to the lower edge of the lower door section 2 and is movable through a series of aligned guide brackets 16 secured to the outer face of the car wall, and limiting upward movement of the lower door section.

Pairs of aligned angle brackets 17 are secured to the car wall below each end of 95 the track 6 and form stops limiting the sliding movement of the door in each direction.

A staple 18 is secured to the lower corner of the section 2 and is engageable by a hasp 19 pivotally mounted on a pin 20. The pin 100 20 is secured to the wall of the car in any appropriate manner and is of sufficient length to permit some vertical adjustment of the hasp 19 in case sagging of the car alters the position of the staple 18.

105 A thin flexible metal bar 21 is pivotally mounted adjacent its center on a pin 22 secured to the lower door section. The bar is adapted to be swung on the pin so that one end is located across the face of each door 110 section, as shown in Figure 1. Angle brackets 23 are provided on the sections 1 and 2

to limit the pivotal movement of the bar. The bar 21 is provided at one end with a transversely positioned eye 24, which, when the bar is in vertical position, registers with a staple 25. A curved pin 26 is secured by a flexible device 27 to a stud 28 in the door section 2 and may be passed through the staple and eye to lock the bar 21 in position.

10 When the car is overloaded, or when it becomes old and the wall A sags or bulges, the door will accommodate itself to the bulge in the car wall, as illustrated clearly in Figure 3. It will thus be possible to slide the door on the track regardless of the bulge in the car and the trouble and delay incidental to jammed doors, will be dispensed with. The flexible bar 21, the sliding hasp 19, the peculiar hinged connection of the iron strips 3 and 4 and the novel method of suspending the door on the track all combine to make this result possible.

15

15

20

Various slight changes might be made in the general form and arrangement of the parts described without departing from the invention, and hence I do not limit myself to the precise details set forth, but consider myself at liberty to make such changes and

alterations as fairly fall within the spirit and scope of the appended claims. 30

I claim:

1. The combination with a freight car, of a door slideable across the outer face of the wall of the freight car, said door comprising two sections hingedly connected, a flexible bar adapted to be positioned across the outer faces of the two sections, means for locking the bar in position, a staple on one of the door sections, a pin spaced from the wall of the freight car, a hasp engageable with the 40 staple, said hasp including an eye encircling the pin and slideable vertically thereon.

2. In a freight car door construction, a door comprising two sections, one of said sections hingedly depending from the other 45 of said sections, a flexible bar pivotally mounted adjacent its center on one section and adapted to have its ends positioned over the faces of the respective sections, a transversely positioned eye on one end of the bar, 50 a staple on one section registering with the eye, and a hooked pin flexibly connected to the door and adapted to be passed through said eye and staple to lock the bar in position.

JAMES LYONS.
